UNITED STATES PATENT OFFICE.

EDGAR D. FELLOWS, OF WATERTOWN, NEW YORK, ASSIGNOR TO THE
DAVIS SEWING MACHINE COMPANY, OF SAME PLACE.

VERTICAL-FEED SEWING-MACHINE.

SPECIFICATION forming part of Letters Patent No. 280,732, dated July 3, 1883.

Application filed February 1, 1883. (No model.)

To all whom it may concern:

Be it known that I, EDGAR D. FELLOWS, of Watertown, Jefferson county, New York, have invented a new and useful Improvement in 5 Vertical - Feed Sewing - Machines, which improvement is fully set forth in the following specification.

This invention relates to the sewing-machines in which the work is advanced by means 10 of one or more vertical feeding devices supported in the head of the machine and movable both vertically and horizontal, and has special reference to the means for imparting the horizontal and lateral movements to the 15 feeding devices.

Ordinarily, as in the well-known Davis sewing-machine, the needle-bar constitutes one of the vertical feeding devices, and in connection with it an auxiliary vertical-feed bar or helper-bar is employed. The invention is shown herein as applied to a machine of this construction, 20 although it is applicable generally to machines of the class indicated.

The invention consists, mainly, in the combination, with the vertical feeding devices and 25 a feed-cam, of intermediate mechanism so constructed and arranged that the device through which motion is conveyed from said cam is always in contact with the latter.

Heretofore in vertical-feed sewing-machines the feed-dog or feed-lever, or the roll carried thereby, is continuously in contact with the cam only when the regulating devices are 30 adjusted to make the longest stitches. At other times—or, in other words, usually—the cam strikes the feed dog or lever and afterward moves away a greater or less distance at each stitch. By the present invention the noise arising from the striking of the 35 cam against the feed dog or lever is avoided.

The invention further comprises certain special combinations of parts, as hereinafter explained.

The accompanying drawings, which form a 45 part of this specification, illustrate the head of a Davis sewing-machine constructed in accordance with the invention.

Figure 1 is a view in vertical cross-section and in elevation, looking to the right, showing 50 the needle-bar, helper-bar, and the mech-

anism for moving the same laterally. Fig. 2 is a view similar to Fig. 1 with the feed mechanism in another position; Fig. 3, a view in vertical longitudinal section on line $x-x$, Fig. 1, with a number of parts in advance as well as behind said line in elevation, looking to the rear, and the needle-cam in section on line $x'-x'$; Fig. 4, a view in vertical cross-section on line $y-y$, Fig. 3, and in elevation, looking to the left; and Figs. 5, 6, and 7, detail views. 55 The same letters in each figure refer to the same parts.

A is the cam house or head of the machine; A', the face-plate; B, the shaft-head or feed-cam; B', the needle-cam roll or driver; C, the needle-bar; C', the needle-cam; D, the feed or helper bar; E and F, feed-levers or bell-cranks; G, the shifting-ledge; J, the spring; L, the regulating-lever; M, the graduated sector, showing length of stitch; N, the handle or knob by 60 which lever L is moved; Q, the shaft; P, the circular disk; R, U, V, W, and X, friction-rolls; S, the line of cloth-plate; Y and Z, studs on which the feed-levers or bell-cranks E and F are pivoted; and H, the feed-spring. 65

The needle-bar C and helper-bar D pass through slots in the roof and floor of the cam-house A, or, more properly, through slots formed in the flanges of the face-plate, and between the said flanges and the corresponding 70 walls of the cam-house. The slot at the top has the roll V at one end, and the said roll, with the side walls and opposite end wall of the slot, form fixed guides, which allow the said bars to swing horizontally or laterally in the 75 plane of the feed movement, (at right angles to the length of shaft Q,) as well as to reciprocate vertically. The slot at the bottom of the cam-house is longer than the combined width of the two bars, so as to permit the swinging 80 motion above mentioned; but its width is equal to their common thickness, so as to keep them in the same plane of motion.

The needle-cam C' is the ordinary grooved heart-cam, and is fixed to the needle-bar. It 85 is engaged by the roll of driver B', which is fastened on the face of the revolving cam B, and which works in the groove in the needle-cam, so as to reciprocate the needle-bar vertically. The needle-bar is so connected with 90

100

the helper-bar and presser-bar that at each descent of the needle-bar the helper-bar is depressed and the presser-bar lifted, and at each ascent the reverse operations take place. The 5 device used for this purpose is or may be the usual bent lever long used in the Davis sewing-machine, which, as it is well known and forms no part of this invention, needs no illustration or particular description. The needle-bar is likewise connected with and operates 10 the take-up in the usual way.

The feed-lever or bell-crank F is supported by and turns upon the stud T, fixed to the inner wall of the cam-house. Its front or longer 15 arm carries the roll R, which bears against the front edge of the needle-bar C.

The feed-lever or bell-crank E is pivoted to the shorter arm of lever F by means of the stud Z. The upright or rear arm carries the 20 roll U, which bears against the cam B. The horizontal or front arm carries the roll W, which works in contact with the shifting-ledge G. This ledge projects from the outer face of the disk P, which is journaled in the inner wall 25 of the cam-house, and is adapted to be turned by the arm L, so as to set the ledge G at the proper inclination or angle. It is by turning this disk and altering the position of the ledge that the lateral stroke of the needle and feed 30 or helper bars, and consequently the length of stitch, is regulated, as hereinafter explained.

The spring J is fastened at one end to a stationary piece in the cam-house, and its free 35 end bears against the upright arm of feed-lever E, tending to turn it upon the stud Z, so as to hold the roll U in contact with the cam B. The feed-spring H bears against the rear edge of the vertical feed or helper bar D, and tends to move it and the needle-bar toward the 40 front of the machine, or, in other words, to restore them to a vertical position.

Fig. 1 shows the position of the feed-levers or bell-cranks with roll U in contact with the smallest diameter of cam-shaped shaft-head B, 45 and the ledge G of the circular disk P in a vertical position. Now, if shaft-head or cam B is rotated in the direction of the arrow, Fig. 2, the high part of said shaft-head or cam, being brought in contact with the roll U, will 50 force said roll back, or to the left in the figure, causing feed-lever or bell-crank E to turn on stud Z and roll W to travel up the face of vertical ledge G. Since the ledge G offers no resistance to the vibration of the lever E on stud Z, no motion will be imparted to lever F and no lateral motion to the vertical feeding 55 devices. Spring J, keeping roll U in contact with cam B, causes roll W to return to the position shown, when roll U again reaches the 60 lower part of cam B.

In Fig. 2 the circular disk P has been turned so as to bring the raised ledge G into a horizontal position. Now, when the high part of the cam comes in contact with roll U, the roll 65 W being prevented from rising by the ledge G, the vertical arm of lever F is forced back,

or to the left in the figure, thereby pressing roll R against the needle-bar C, and causing the needle and feed bars CD to move laterally into the position shown in the said Fig. 2. 70 When the cam B revolves so as to bring the roll U in contact with its low side, roll R travels along the ledge G, permitting the lever F to return to the position shown in Fig. 1. The spring H, keeping the needle and feed 75 bars against the roll R, returns them to a vertical position. The upper ends of the needle and feed bars being held in fixed guides, they are caused to incline from a vertical position when moved laterally by roll R. Now, it will 80 be observed that with the disk P in the position shown in Fig. 1, bringing the projecting ledge into a vertical position, the shaft Q and cam B may be rotated without moving lever F and without imparting any lateral movement to the needle and feed bars, at the same time keeping roll U in constant contact with the cam B, thereby preventing any slapping or rebounding against cam B, and its consequent noise, to overcome which is one of the 85 principal objects of this invention. It will be further seen by reference to Fig. 2 that the disk P in the position as shown bringing the projecting ledge G in a horizontal position, the roll R communicates lateral motion enough to the 90 needle and feed bars to produce a very long 95 stitch. With disk P shifted so as to bring ledge G at any angle between a horizontal and a vertical position, the movement of bell-crank F will be correspondingly less, and the length 100 of stitch can be thereby regulated as desired. The position of the arm L above the graduated sector M indicates the length of stitch.

The face of the projecting ledge G, on which the roll W travels, is the part of a circle 105 whose center is at the center of the stud Z, and when roll U is in contact with the low side of cam B the center of roll W comes exactly over the center of disk P; which insures the needle and feed bars being brought exactly to 110 a vertical position when they return, on any and all lengths of stitch.

The feed-cam B, the needle-cam C', and the needle-cam roll or driver B' are so arranged 115 that the roll R and the vertical bars C D are moved in the direction of the feed (to the left, Figs. 1 and 2) after the needle-bar and helper-bar have descended, and that the reverse or return movement under the pressure of spring H is allowed to take place after the foot of the 120 helper-bar and the needle have been raised clear of the work.

As shown, the shaft Q runs toward the operator, who sits at the front of the machine. The effect of this is that the needle-cam roll 125 or driver, by its action on the needle-cam aids in returning the needle-bar to a vertical position, and in holding it in that position during its descent, instead of tending to displace it, as it would do if the shaft were run 130 in the opposite direction.

For a full explanation of the operation ref-

erence may be had to the patent of Wm. S. Carlisle, for improvements in vertical or top feed sewing-machines, dated January 9, 1883, and numbered 270,540. The new feed mechanism herein described could, however, the 5 position of the feed-cam on the shaft being properly changed, be used in a machine having the shaft run in the opposite direction, the needle-bar being pivoted on the face of an auxiliary 10 cam-bar, as described in patent to Job A. Davis, No. 58,614, October 9, 1866, or the disturbing effect of the roll or driver being neutralized or avoided by other suitable means.

The parts of the machine not shown may be 15 of the ordinary or of other suitable construction.

Modifications may be made in the details of construction without departing from the spirit of the invention, and parts of the invention 20 could be separately used, if desired.

The term "vertical feeding devices" is employed herein to include one or more such devices.

Having now fully described my said invention and the manner of carrying the same into 25 effect, what I claim is—

1. The combination, with vertical feeding devices and a feed-cam placed in the cam house or head of a sewing-machine, of operating and 30 adjusting mechanism, as explained, the same comprising reciprocatory parts in continuous contact or connection with said vertical feeding devices and feed-cam, and with each other, and adjusting means for changing the length 35 of stroke imparted to said feeding devices while maintaining the contacts or connections aforesaid unbroken, substantially as described, whereby a noiseless feed is produced.

2. The combination, with the needle-bar and 40 helper-bars, both of them movable vertically and laterally, of operating and adjusting mechanism for imparting and regulating the lateral movement of said feeding devices, said mechanism comprising reciprocatory parts in continuous contact with each other and with said feed-cam and needle-bar, and adjusting means for varying the stroke of the latter without 45 breaking the said contact or connection and without altering the position of the needle-bar 50 at its descent, substantially as described.

3. The combination, with feeding devices and a feed-cam, of a lever turning on a fixed center, and having a contact or connection with 55 said devices, and a second lever pivoted to and carried by the former, and having a contact or connection with said feed-cam, and an adjustable fulcrum-piece for said second lever, substantially as described.

4. The combination, with feeding devices and a feed-cam, of two bell-crank levers, one 60 pivoted to and carried by the other, and an adjustable fulcrum-piece, substantially as described.

5. The combination of vertical feeding devices, a feed-cam, a feed-lever, a spring for 65 holding one arm of said lever in contact with said cam, the shifting-ledge, and means, as indicated, for conveying motion from said feed-lever to the feeding devices, said parts being all placed in or carried by the cam house or 70 head of the sewing-machine, substantially as described.

6. In a vertical-feed sewing-machine, the combination, with a feed-lever and an adjustable bearing or fulcrum-piece therefor—such as 75 the shifting-ledge described—of the regulating lever-arm and the graduated sector, said lever and said adjustable bearing or fulcrum-piece being within the cam house or head of the machine and said regulating-arm and sector on 80 the outside of the same, substantially as described.

7. In a vertical-feed sewing-machine, and in combination with the vertical feeding devices, their operating mechanism, and the regulating 85 means for changing the lateral stroke of said devices placed within the cam house or head of the machine, a graduated sector, and a regulating index-arm connected with said regulating means, and placed, together with said sector, on the outside of said cam house or head, 90 substantially as described.

8. The combination of the disk journaled in the wall of the cam-house, the regulating-arm attached thereto on the outside, the graduated 95 sector, the projecting ledge attached to said disk on the inside, the feed-levers, feed-cam, and vertical feeding devices, substantially as described.

9. The combination, with the vertical feeding devices, of the feed-cam, the feed-lever acting against the said devices, the feed-lever pivoted to the former lever and acted upon by the said cam, the spring bearing against the second feed-lever, the shifting-ledge forming 100 an adjustable bearing or fulcrum-piece for the same, and the feed-spring, substantially as described.

In testimony whereof I have signed this specification in the presence of two subscribing 110 witnesses.

EDGAR D. FELLOWS.
